UNITED STATES PATENT OFFICE

2,422,653

METHOD OF BURNING LIQUID
HYDROCARBON

James E. Breece and Bruce Hayter, Santa Fe,
N. Mex., assignors to Oil Devices, Santa Fe,
N. Mex., a limited partnership of Illinois

Original application May 11, 1942, Serial No.
442,414. Divided and this application November
15, 1943, Serial No. 510,304

5 Claims. (Cl. 158—117.5)

1

Our invention relates to an improvement in oil burning and has for one purpose to provide an improved method of burning liquid hydrocarbon fuels.

Another purpose is to provide the method of burning liquid hydrocarbon in which the liquid hydrocarbon to be burned is positioned in or delivered to a vaporizing zone in which it is entirely surrounded by a burning mixture of vaporized hydrocarbon and air.

Another purpose is to provide an improved method of vaporizing liquid hydrocarbons for combustion.

Other purposes will appear from time to time in the course of the specification.

The present application is a division of our copending application Serial No. 442,414, filed May 11, 1942, now Patent No. 2,348,721, dated May 16, 1944.

The invention is illustrated more or less diagrammatically in the accompanying drawings, wherein:

Figure 1 is a plan view of our burner as applied to a cook stove;

Figure 2 is a vertical section on a larger scale, taken along the line 2—2 of Figure 1;

Figure 3 is a top plan view of the structure shown in Figure 2;

Figure 4 is an end view with parts broken away of the structure shown in Figure 3, with the addition of the fan unit which is shown in Figure 2 but is omitted from Figure 3.

Like parts are indicated by like characters throughout the specification and drawings.

It will be understood that, whereas the invention is shown as applied to a cook stove, it may be applied to any other suitable heating unit, such as a furnace or a space heater.

Referring to the drawings, 1 generally indicates a heater to which the burner is applied. 2 is any suitable front member of such a heater, with an inlet aperture 3. 4 indicates grate bars of a conventional cook stove to which the burner is applied, but the bars have no function when our heater is used, and may be removed. 5 is a base or supporting plate, which may be secured to the front member 2 of the stove by any suitable means, for example the bolts 6. The plate 5 is centrally apertured as at 7, and this aperture for convenience may be circular and of smaller diameter than the aperture 3 in the stove. The plate 5 is provided with any suitable spacing means, for example lugs 8. Against these is drawn a burner proper which includes the abutting flame ring 9, herein shown as having a cen-

2

tral flame aperture 10 of substantially smaller diameter than the aperture 7 of the plate 5.

11 is an inwardly extending annular flange spaced inwardly somewhat within the aperture 7 to provide an air inlet ring or clearance 12. Associated with the flame ring 9 is an outer cylinder 13, with its end 14 and air inlet aperture 15. 16 is a burner pot with an end 17 and a generally cylindrical side wall formed with a plurality of primary air inlet apertures 18 located at various distances from the end 17. If desired, the end 17 may also have air inlet apertures. Any suitable means for admitting secondary air may be employed, but we illustrate a single row of secondary air inlets 19 which are inwardly tilted toward the open end of the pot. Also, the clearance or gap 12 may be used to admit secondary air.

20 is a vaporizing pan herein shown as open topped. 21 is a fuel pipe extending thereto and also adapted to serve as a support therefor, although the pan may be additionally supported or centered by a connection with the side or bottom of the pot. We illustrate for example in Figure 2 a clip 22, which may be welded or otherwise secured to the pan 20 and may be welded or bolted, as at 23, to the pot bottom 17. The fuel pipe 21 is shown as extending to a T-connection 25, by which it is connected to any suitable float chamber or other fuel control device, indicated at 26.

The rate of flow may be controlled for example by the exterior manual element 27, although it will be understood that the control may be automatically maintained as desired. Any suitable means not herein shown in detail may be employed for delivering fuel from a suitable source to the chamber 26, and a float valve or other suitable means may be employed for maintaining a predetermined oil level within the chamber 26. The chamber 26 and its associated parts may be mounted upon the outer member 13, for example by brackets 28. It will be understood, of course, that the control chamber 26 may be otherwise supported, but it is advantageous that the entire unit be mounted or supported, directly or indirectly, upon the heater unit or upon the plate 5, so that the entire structure may be unitarily withdrawn from the stove. Any convenient means for securing the structure to the stove may be employed, but we illustrate for example tie rods 30, screw threaded to the plate 5 and provided with upturned locking ends 31, abutting 35 against the bottom 14 of the outer cylinder.

Aligning or centering studs 32, in addition to the tie rods may be provided.

It will be understood that any suitable means may be employed for supplying air either by natural draft or under pressure. However, Figures 1, 2 and 4 illustrate a preferably removable booster motor and fan unit. Longitudinal vanes 33 are provided in the space between the cylinder 13 and the pot 16 to assist in directing air longitudinally through said space and for preventing eddy currents.

It will be realized that whereas we have shown practical means for carrying out our invention, nevertheless a variety of different structures may be employed. What is essential is that some means be provided for maintaining a supply of liquid fuel and for subjecting liquid fuel to the heat of combustion in a zone in which the liquid fuel is entirely surrounded by vaporized mixture.

The use and operation of our invention are as follows:

In the operation of the device and assuming that the user wishes to initiate combustion, a supply of fuel is admitted to the pan, and it may be ignited by dropping a match into the pan. When minimum combustion is desired, the motor and fan unit is removed or left switched off. Once combustion is initiated, the primary air admitted through the apertures 18 mixes with the hydrocarbon vaporized by the heat of combustion to form a primary mixture. This primary mixture circulates toward the flame aperture 10. If the fuel supply is kept to a minimum, the apertures 18 will admit also sufficient air for the secondary air supply, and the completed mixture will burn within the pot not far from the top of the pan. When the fuel supply is increased, the apertures 18 provide primary air for the mixture, and the secondary air to complete the mixture may be delivered either through the apertures 19 of the form of Figure 2, or through the gap 12 between the members 5 and 11, or through both. The amount of fuel which can be vaporized and burned can be increased by the employment of means for increasing the air pressure or air passage through the device, and the practical means for that purpose is the motor and fan unit shown. When full air pressure is used in connection with maximum fuel oil delivery, a blast of flame extends generally horizontally into the stove, and in practice is of sufficient length fully to heat the stove compartment illustrated at "X" in Figure 1.

It will be observed that the primary air is admitted all the way around the vaporizing pan both above and below it. In the forms of the device herein shown, the bottom 17 is left unbroken, but it will be understood that air may, if desired, be admitted through the bottom. It will be observed that we provide a vaporizing vessel subjected to the heat of combustion, which is entirely surrounded by means for admitting primary air. Preferably an open topped vessel is used, but it may in some circumstances be convenient to use a vessel the top of which is partially covered. While the axis of the pot may be varied, or, in other words, the axis along which the air is delivered and the flame is directed, we find it advantageous in many practical installations to provide a pot the axis of which is generally horizontal or generally parallel with the surface of the oil being vaporized in the pan.

In normal high stage operation, the completed mixture is burning at or slightly to the right of the secondary air inlets 19, referring to the posi-

tion of the parts as shown in Figure 2. The radiant heat of this combustion strikes the side and bottom of the pan 20 and even penetrates to the upper surface of liquid within the pan. The pan is entirely surrounded by the primary mixture. Particularly at the lower stages of combustion, combustion may be taking place entirely about the pan 20. The pan 20 is preferably of heat conductive material such as metal and constitutes a highly efficient means for vaporizing the liquid fuel.

It will be understood that whereas we admit the liquid fuel along the pipe 24, any suitable means may be employed for delivering the fuel to the pan 20. It will also be understood that we do not wish to be limited to any specific vaporizing means. What is essential is that the liquid hydrocarbon be delivered to an area where it is subjected to the radiant heat of combustion going on about it and near it.

We claim:

1. The method of combustion which includes providing a volume of liquid hydrocarbon for vaporization in a vaporizing zone, continuously supplying additional liquid hydrocarbon to said zone to take the place of the hydrocarbon vaporized in such zone, maintaining a mixing zone substantially entirely surrounding said zone of vaporization, delivering primary air in relatively small and widely scattered jets, upwardly, downwardly and laterally into said mixing zone, causing the primary mixture thus formed to move away from the vaporizing zone, delivering secondary air into said primary mixture at a zone spaced away from the mixing zone, and burning the final mixture thus formed, and employing part of the heat of combustion of the final mixture to vaporize the liquid hydrocarbon in the vaporizing zone.

2. The method of combustion which includes providing a volume of liquid hydrocarbon for vaporization in a vaporizing zone, continuously supplying additional liquid hydrocarbon to said zone to take the place of the hydrocarbon vaporized in such zone, maintaining a mixing zone substantially entirely surrounding said zone of vaporization, delivering primary air in relatively small and widely scattered jets, upwardly, downwardly and laterally into said mixing zone, from above and below and at the sides of said vaporizing zone, convergently about and toward the vaporizing zone, causing the primary mixture thus formed to move away from the vaporizing zone, delivering secondary air convergently into said primary mixture at a zone spaced away from the mixing zone, and burning the final mixture thus formed, and employing part of the heat of combustion of the final mixture to vaporize the liquid hydrocarbon in the vaporizing zone.

3. The method of combustion which includes providing a volume of liquid hydrocarbon for vaporization in a vaporizing zone, continuously supplying additional liquid hydrocarbon to said zone to take the place of the hydrocarbon vaporized in such zone, maintaining a mixing zone substantially entirely surrounding said zone of vaporization, delivering primary air in relatively small and widely scattered jets, upwardly, downwardly and laterally into said mixing zone, from above and below and at the sides of said vaporizing zone, causing the primary mixture thus formed to move away from the vaporizing zone, delivering secondary air convergently into said primary mixture at a zone spaced away from the mixing zone, along a path extending away from the

vaporizing zone, and burning the final mixture thus formed, and employing part of the heat of combustion of the final mixture to vaporize the liquid hydrocarbon in the vaporizing zone.

4. A method of combustion which includes maintaining a supply of liquid fuel in a zone of vaporization, subjecting said fuel, in said zone of vaporization, to both conducted and radiant heat of combustion occurring about and adjacent said zone of vaporization, delivering sufficient primary air to a space substantially surrounding said zone of vaporization to form, with the vaporized fuel, a primary mixture, causing a partial combustion of said primary mixture, causing said primary mixture to move away from said zone of vaporization, thereafter mixing with said primary mixture sufficient secondary air to provide a final and fully combustible mixture, burning said mixture at a distance from said zone of vaporization sufficiently small to subject the fuel in said zone of vaporization to some of the heat of said final combustion, and employing part of said heat of final combustion to vaporize the liquid fuel in said zone of vaporization.

5. A method of combustion which includes maintaining a supply of liquid fuel in a zone of vaporization, subjecting said fuel, in said zone of vaporization, to both conducted and radiant heat of combustion occurring about and adjacent said zone of vaporization, delivering sufficient primary air to a space substantially surrounding said zone of vaporization to form, with the vaporized fuel, a primary mixture, causing a partial combustion of said primary mixture, causing said primary mixture to move away from said zone of vaporization along a predetermined path, thereafter delivering convergently about the pri-

mary mixture, as it moves along said path, a supply of secondary air sufficient to provide a final and fully combustible mixture, burning said mixture at a distance from said zone of vaporization sufficiently small to subject the fuel in said zone of vaporization to some of the heat of said final combustion, and employing part of said heat of final combustion to vaporize the liquid fuel in said zone of vaporization.
